UNITED STATES PATENT OFFICE.

CLIFTON W. SHERMAN, OF BUFFALO, NEW YORK, ASSIGNOR TO THE NATIONAL MAL-
LEABLE CASTINGS COMPANY, OF CLEVELAND, OHIO, A CORPORATION OF OHIO.

FRICITION DRAFT-RIGGING.

1,169,434.

Specification of Letters Patent.

Patented Jan. 25, 1916.

Application filed January 20, 1911. Serial No. 603,672.

To all whom it may concern:

Be it known that I, CLIFTON W. SHERMAN, a citizen of the United States, residing at Buffalo, in the county of Erie and State 5 of New York, have invented new and useful Improvements in Friction Draft-Rigging, of which the following is a specification.

This invention relates to a cushioning device for railway draft riggings and buffers 10 and more particularly to that class of draft riggings for railway cars in which the yielding resistance of the springs is supplemented by frictional engagement of the shoes with relatively stationary surfaces the same being 15 generally known as friction draft gears.

Although such friction draft gears as heretofore constructed were superior to draft gears which only employed springs, the constantly increasing weight and capacity of 20 the cars has subjected these gears to such an impact when coupling the cars and when starting the same that the means heretofore provided to save the equipment from undue wear has been found insufficient. Owing to 25 the standardization of the present system of car construction it is impossible to add a greater amount of spring cushion because the space available for the installation of draft gearing has been exhausted.

It is the object of this invention to provide 30 a draft rigging or gearing which can be installed within the space now available under the M. C. B. rules or dimensions and provide a large increase in the frictional resistance 35 to the movement of the draw bars of the cars without any increase in the cost of manufacture, installation or maintenance.

In the accompanying drawings, consisting 40 of 2 sheets: Figure 1 is a fragmentary horizontal longitudinal section of the draft rigging of a railway car embodying my invention. Fig. 2 is a vertical longitudinal section of the same. Fig. 3 is a vertical transverse section in line 3—3, Fig. 1. Fig. 45 4 is a detached front view, of one of the spreading wedges or cores of one set of inner movable friction or brake members. Fig. 5 is a side view of the same. Fig. 6 is a detached view from the inner side thereof of 50 one of the shoes of one set of inner friction members. Fig. 7 is an outer side view of the same.

Similar letters of reference indicate corresponding parts throughout the several 55 views.

Referring to the drawings, 1, 1, represent the draft sills or beams of the car which are arranged lengthwise and parallel underneath the body of the car, 2 and 3 the front and rear followers which are guided on said sills so as to be capable of moving horizontally forward and backward, 4 a pair of front stops or blocks secured to the inner sides of the sills and operating to limit the forward movement of the front follower, 5 a pair of rear stops or blocks secured to the inner sides of the sills and operating to limit the rearward movement of the rear follower, 6 the draw bar or coupler shank arranged lengthwise in front of the front follower and 7 the strap or yoke connected with the draw bar and loosely or slidably embracing the front and rear followers. These parts may be of any suitable and well known construction.

That part of the draft rigging or gearing which embodies my invention is constructed as follows:—The friction member 8, which I have shown in the form of a cylindrical casting, is arranged horizontally and lengthwise between the sills and supported between the longitudinal parts of the strap or yoke. The rear end of the friction member 8 engages with the front side of the rear follower, and is provided with a forwardly-facing shoulder 9, while the front end thereof is separated from the rear side of the front follower by an intervening space or clearance. The friction member 8 forms the friction or brake member, and is incapable of lateral movement. Engaging the rear shoulder 9 of the friction member 8 is a spring cushion, which preferably consists of two coil springs 10 and 11 of different diameters, the smaller one 10 being arranged axially within the larger one 11. At the forward end of the friction member 8, and adjacent to the spring cushion, are arranged wedging friction members which coöperate with the spring cushion and the member 8 for absorbing, cushioning or relieving the impact against the car. These wedging friction members comprise a plurality of sets of such members, each set constituting a complete friction device. Although the 105 number of sets of wedging friction members may be varied, two sets of such members, an outer or front set and an inner or rear set, as shown in the drawings, are preferred.

Each set of wedging friction members preferably comprises a plurality of friction or brake shoes 12, preferably three in number, arranged in an annular row and each 5 having a friction face 13, an inclined or wedging face 14 and a wedging member 15 arranged against the annular row of shoes and provided with a plurality of inclined faces 16, each of which engages with the inclined face of one of the companion shoes. The large ends of the shoes are provided 10 with flat transverse faces 17, and the large end of the wedge member 15 is provided with a flat transverse face 18.

15 As shown in Fig. 1, the two sets of wedging friction members are arranged in tandem and the flat faces at the large ends of the rear set of shoes bear against the front ends of the spiral springs of the cushion device, and the flat faces on the large ends of 20 the front set of shoes engage with the flat face of the large end of the rear wedge, while the flat face of the large end of the front wedge bears against the rear side of 25 the front follower.

The friction member 8 and the two sets of friction members are connected so as to be capable of axial movement relatively to each other, preferably by means of a longitudinal tie rod or bolt 20, arranged centrally within the springs, friction member and wedges, and provided at its opposite ends with shoulders 21, 22, formed by the head and nut thereof, which engage, one 30 with the larger side of the rear end of the friction member and the other with the larger side of the front wedge of the wedging friction member.

In the assembled condition of the parts, 40 the springs and one set of wedging friction members are arranged wholly in engagement with the friction member 8, while the outer set of wedging friction members is arranged only partway in engagement with 45 the friction member and projects forwardly therefrom.

When the draw-bar or coupler shank is moved backward by the impact with another draw-bar or coupler, the rear follower remains at rest and forms the abutment which 50 receives the thrust; while the front follower moves rearwardly. During this movement the wedges, by reason of the engagement of their inclined faces with the corresponding 55 faces of the companion shoes, causes the latter to be wedged and their friction faces to bear with increased frictional pressure against the friction face of the friction member 8.

60 While the shoes of both sets of wedging friction members are thus wedged into frictional engagement with the friction member 8, the frictional resistance to the backward movement of the draw-bar thus produced is 65 added to the resistance of the springs, and

the total resistance offered to the impact from the draw-bar by the use of two sets of wedging friction members is very much greater than would be obtained if one set of such members, but equaling in length the 70 two, were employed. The coöperating inclines of the wedges and shoes are at such an angle as to enable the wedges of both sets of wedging friction members to force such shoes against the friction member, and thereby multiply the frictional contact between the same, and still permit the wedges to release or withdraw freely from the shoes instead of sticking. By thus employing a plurality of independent sets of wedges and 80 shoes, the frictional grip on the friction member 8 is multiplied, thereby enabling the rigging to withstand much greater strains or shocks than has been possible by the use of the friction gears as heretofore 85 constructed.

It is thus possible to increase the capacity of the cushioning device without any increase in the weight of the rigging or the cost of manufacture, and without complicating the structure or departing from the general lines laid down by the railroad regulations governing the interchanging of parts, and without making the angle of the wedges and shoes so sharp as to interfere 95 with their proper release.

The frictional capacity of this device is dependent directly upon the resistance behind each set of shoes and a wedge, and the springs constitute the sole means of resisting the inward movement of the rear shoes and wedge, and therefore control the friction wedging movement of the rear shoes, while the combined compression of the 100 springs and the frictional capacity of the rear shoes and wedge resist the forward or inward movement of the front set of shoes and wedge, and control the frictional wedging movement of the front shoes, thereby intensifying the spring action and frictional 110 resistance and multiplying the capacity of the gear accordingly.

When the draw-bar is pulled forward, the front follower becomes the abutment, in which case the friction member 8 and 115 springs are moved toward the two sets of wedging friction members, and the wedging of the shoes by the wedges is effected. When the impact on the cushioning device has spent itself, the followers are separated 120 one from the other by the expansion of the springs, and at such time the wedges release themselves from the shoes, and the shoes in turn release their grip on the friction member 8.

125 The terms and expressions which I have employed are used as terms of description and not of limitation, and I have no intention, in the use of such terms and expressions, of excluding any mechanical equiva-

lents of the features shown and described, or portions thereof, but recognize that various structural modifications are possible within the scope of the invention claimed.

5 I claim as my invention:

1. In a frictional shock absorbing mechanism, a longitudinally-extending friction member having at one end a broad flat base adapted to impart movement in one direction to the friction member, sets of friction shoes, each set of shoes consisting of at least three shoes and being arranged radially about a common longitudinal axis and each shoe having two longitudinally-extending faces which converge toward said axis, wedge members engaging said shoes, and a compression spring, said wedges and sets of shoes being arranged alternately and in tandem; a wedge between successive sets of shoes having a wedging engagement with the set of shoes between it and the compression spring and having substantially non-wedging engagement with the set of shoes remoter from said spring.
2. In frictional shock absorbing mechanism, a longitudinally-extending friction member having its friction surface substantially parallel with the longitudinal movement of the friction parts, sets of shoes in frictional engagement with said member, each set of shoes consisting of at least three shoes arranged radially about a common longitudinal axis, each shoe being intersected by a longitudinally-extending plane coinciding with said axis, said plane being out of coincidence with any other plane passing through said axis and through any two of the other shoes in the same set, wedge members in engagement with said shoes, and a compression spring, said wedges and sets of shoes being arranged alternately and in tandem, each wedge having a wedging engagement with only one set of shoes.
3. In frictional shock absorbing mechanism, a longitudinally-extending friction member having at one end a broad flat base

adapted to impart movement in one direction to the friction member, sets of friction shoes, each set of shoes consisting of at least three shoes and being arranged radially about a common longitudinal axis and each shoe having two longitudinally-extending faces which converge toward said axis, wedge members engaging said shoes, and a compression spring, said wedges and sets of shoes being arranged alternately and in tandem, the said wedges having inclined wedging faces coöperating with inclined wedging faces on said shoes for forcing the sets of shoes into frictional engagement with said member, each wedge being provided with a flat transverse bearing to prevent sticking during the releasing operation.

4. In frictional shock absorbing mechanism, a main friction member having longitudinally-extending surfaces, sets of friction shoes in frictional engagement with said surfaces, each of said sets comprising at least three shoes arranged radially about a common longitudinal axis, wedge members engaging said shoes, said wedges and sets of shoes being arranged alternately and in tandem, and a compression spring, the intermediate wedge between successive sets of shoes having wedging surfaces engaging corresponding surfaces on the set of shoes between it and said spring, said engaging surfaces extending at an acute angle to the longitudinally-extending surfaces of the said main friction member, said intermediate wedge also having non-wedging surfaces engaging corresponding surfaces on the set of shoes farther removed from said spring, said surfaces extending substantially at right angles to the surfaces on the main friction member.

Witness my hand this 18th day of January, 1911.

CLIFTON W. SHERMAN.
